UNITED STATES PATENT OFFICE.

JOHN GEORGE GLOVER, OF LACHINE, QUEBEC, CANADA.

BELL AND SWITCH OPERATING MEANS.

1,174,492.

Specification of Letters Patent. Patented Mar. 7, 1916.

Application filed April 23, 1915. Serial No. 23,396.

To all whom it may concern:

Be it known that I, JOHN GEORGE GLOVER, a subject of the King of Great Britain, residing at No. 143 Notre Dame street, Lachine, Province of Quebec, Canada, have invented certain new and useful Improvements in Bell and Switch Operating Means; and I do hereby declare that the following is a full, clear, and exact description of the invention, such as will enable others skilled in the art to which it appertains to make and use the same.

The invention, to be hereinafter described relates to bell and switch operating means.

In order to more clearly disclose the construction, operation, and use of the invention, reference should be had to the accompanying drawings forming part of the present application.

Throughout the several figures of the drawings like reference characters designate the same parts.

The single figure of the drawings is a central longitudinal section through the device.

The main objects of the invention are, to provide a neat, compact, efficient, and durable means for ringing electric door bells, and the like, and, at the same time, lighting a light within the house, which means may also be used as an ordinary push button switch from within the house, if desired.

Referring to the drawings in detail, 1 designates a push button casing of suitable construction which is secured on the outer face

35 of the door frame 2, in the usual manner. A rod 3 of suitable non-conductive material is slidably operative through the door frame and projects, at its outer end, into the casing 1, so as to normally engage the inner end of 40 the push button 4. The inner end of this rod projects into a cylindrical boxing 5, of suitable material, set into the inner face of the door casing or frame, and engages one arm of a yoke 6 pivotally mounted on a standard 45 7 secured in the casing and held in proper position by tension springs 8 secured to the inner end of each arm thereof and to the inner end of the standard.

A contact plate 9 is secured around rod 3, 50 in the casing 1, in such a position that, when the button 4 is pushed inwardly, it will contact with the two terminal posts 10 secured in the bottom of the casing. These two posts are connected with the wires 11 and 11^a of 55 the two sides of a bell circuit so that, by pushing the button, the bell is rung in the

usual manner. The rod 3 is normally held out by the action of a coil spring 12 mounted thereabout and confined between the bottom of casing 1 and a pin passed through 60 the rod.

When rod 3 is forced inwardly it raises one arm of yoke 6 and depresses the other arm so as to force a cylindrical head 13 carried thereby between two spring contacts 14 secured to the bottom of casing 5, which cooperates to form a spring clip. When the pressure on rod 3 is released the balance tension springs 8 act to hold the head 13 in close contact with members 14 which are directly connected to binding posts 15 connected to the opposite sides of a light circuit controlling a hall light, or the like. By this means, the hall light, or, if preferred, a porch light, is lighted when the bell is rung 75 and it is possible to see who is at the door, or to have a light in the hall, as desired. To turn off the light it is only necessary to push in the inside button 16 of the boxing 5 which was forced out when the light was 80 turned on. If it is desired to light the light from inside the house the button 17 is pushed in. This operation in no way affects the bell circuit and serves the same purpose as an ordinary push button switch. 85

It is thought that the construction, operation, and use of the invention will be clear from the preceding detailed description.

Changes may be made in the construction, arrangement, and disposition of the 90 several parts of the invention without in any way departing from the field and scope of the same as defined in the appended claims, and it is meant to include all such within this application wherein only a preferred 95 form has been disclosed.

Having thus fully described my invention, what I claim as new and desire to secure by Letters Patent is:

1. In a device of the character described, 100 a casing, terminal posts mounted therein, a boxing, a spring clip mounted therein and adapted to be connected to an electric circuit, a pivotally mounted yoke provided on one arm with a member adapted to engage 105 with the said spring clip when such arm is depressed, means for depressing the arm of the yoke provided with the spring clip engaging member and for electrically connecting the said terminal posts, and independent means for rocking the said yoke in 110 either direction on its pivot.

2. In a device of the character described, a casing, terminal posts mounted therein, a boxing, spring contacts mounted therein so as to form a spring clip and adapted to be connected to an electric circuit, a yoke pivotally mounted in the said casing and provided on one arm with a head adapted to engage the said spring clip when that arm is depressed, a rod having its inner end normally in contact with one arm of the said yoke and its outer end operative in the said casing, means for normally holding the said rod out, means for forcing the said rod inwardly, means for establishing electrical connection between the terminal posts in the said casing when the rod is forced inwardly, and means for raising the depressed arm of the said yoke.
3. In a device of the character described; a casing; terminal posts mounted therein; a boxing; a standard mounted therein; a yoke pivotally mounted thereon and provided, on one arm, with a cylindrical head;

spring contact members mounted in the said boxing, beneath the said head, and adapted to be connected to an electric circuit; a slidably operative rod having one end extending into the said boxing and in contact with the arm of the said yoke not provided with the head, and its other end extending into the said casing; a coil spring mounted about the said rod and adapted to hold it out; a contact plate carried by the said rod and adapted to electrically connect the said terminal posts in the casing when the rod is forced inwardly; a push button mounted in said casing in contact with the outer end of said rod; and push buttons mounted in the said boxing normally in contact with the arms of the said yoke.

In witness whereof I have hereunto set my hand in the presence of two witnesses.

JOHN GEORGE GLOVER.
